UNITED STATES PATENT OFFICE.

BYERS W. KADER, OF ROANOKE, VIRGINIA.

DOOR-OPERATING MECHANISM FOR DUMP-CARS.

1,071,750.

Specification of Letters Patent.

Patented Sept. 2, 1913.

Application filed December 23, 1912. Serial No. 738,216.

To all whom it may concern:

Be it known that I, BYERS W. KADER, a citizen of the United States, residing at Roanoke, in the county of Roanoke and State of Virginia, have invented certain new and useful Improvements in Door-Operating Mechanism for Dump-Cars; and I do hereby declare the following to be a full, clear, and exact description of the invention, such as will enable others skilled in the art to which it appertains to make and use the same.

My invention relates to improvements in mechanism for operating the hinged doors which close the openings in the sides or bottoms of dump cars through which the contents of the car are dumped, and my invention has for its object to provide simple and effective means for relieving torsional strain on the winding shaft by which such doors are operated.

With this object in view my invention consists in the construction and arrangement of elements hereinafter described.

Referring to the drawings: Figure 1 is a fragmentary vertical longitudinal section of a side dump hopper car with my device applied, said section being taken on the line A B, Fig. 2. Fig. 2 is a transverse vertical section of the same, taken on the line C D, Fig. 1. Fig. 3 is a top plan view of one of the doors and its connections as applied, in a modified form, to a drop door of a flat bottom car. Fig. 4 is a transverse section of the same. Fig. 5 is a side view, and Fig. 6 a vertical sectional view showing a modified form of my invention as applied to a drop bottom hopper car in which two doors operating together in unison are used. Fig. 7 is a detail side view of the hook of my invention. Fig. 8 is a transverse sectional view of the hook of my invention taken on the line E F, showing the chamfered edges of the same.

In the drawings, 1 is a winding shaft extending longitudinally of the car below the center sills 2 and supported by brackets 3 from the center sills. The winding shaft is adapted to be operated by a hand wheel 4 at the end of the car, connected to the winding shaft by shafts 5 and 6 and universal joints 7 and 8. The winding shaft is provided at suitable intervals with winding drums 9 to which are secured chains 10 and to the free ends of the chains are secured hooks 11, the rear ends of which in turn are con-

nected links 12. The links 12 are connected at their other ends to the doors 13 which are hinged to the sides of the car at 14 so as to close the opening between the side of the car and the inclined bottom 15. The hooks 11 shown in detail in Fig. 7 are so shaped as to fit over the winding drum so that the hook bears upon the drum at such a point on the periphery of the same that the line of strain, which is the line drawn from this point to the point of attachment of the link 12 to the door, will fall beyond the center of the drum, but not sufficiently beyond the center of the drum as to hold against dislodgment when the winding drums are turned to unwind the chains 10 when it is desired to release the doors 13 for dumping the contents of the car. The end of the hook that bears upon the drum to sustain the load is constructed in the shape of a portion of a circle at 27 and this circular portion bearing upon the outer periphery of the drum 9 will cause the contact between the hook and the drum to be made on substantially a line, longitudinally of the drum, at 28. This will insure that the point of contact 28 will fall beyond the center of the drum, even though there may be considerable irregularity in the parts as manufactured. From this point where the hook bears upon the drum to sustain the load, the hook is cut back so that it clears the drum until it reaches a point near the top or bottom of the drum, as the case may be, where it again comes in contact with the drum, but merely to rest thereon. The outer end of the hook is provided with a series of holes (22) for pivotal connection with the link 12, a series of holes 23 in the link 12 being spaced at slightly greater intervals than those in the hook. When the various holes in the two series are matched by means of the connecting pin 24 a very delicate adjustment of the combined length of the link and hook is obtained. As the chain 10 is wound upon the drum 9 and the hook 11 drawn toward the drum it is possible that the forward edge 25 of the hook may attempt to climb up over the chain instead of over the drum. To avoid this the forward edge 25 of the hook is chamfered at both sides at 26 so that the hook will be deflected from the chain and will be drawn around into its normal position on the drum. This construction is shown in detail by Figs. 7 and 8. It will of course be understood that in order that both

doors 13 may be simultaneously opened or closed it will be necessary to have the two chains arranged to wind one upon the upper side of the winding drum and the other on the lower side.

In operation, the doors 13 being opened the hand wheel 4 will be rotated and will cause the winding shaft 1 to rotate winding the chains 10 upon the winding drums 9 and, through the hooks 11 and links 12, drawing the doors inward against the edges of the inclined bottom 15. The chains 10 are of such length that as the doors come in contact with the edges of the inclined bottom 15, the hooks will be in position to embrace the winding drum above described, with the line of strain slightly beyond the center of the drum or shaft, that is, the line passing through the pivot point on the door and the point of contact between the hook and the drum. When in this position the strain on the door due to the pressure upon it of the contents of the car will be sustained by the hook as a direct pull upon the winding drum, the pull in one direction of one door being, however, balanced by the pull of the other hook since the hooks of both chains embrace the winding drum. All torsional strain on the winding drum will be thus avoided. The links 12 are so connected with the hooks 11 as to hold the hooks from swiveling. The connection may be a pivotal or rigid connection. The point at which the chain is connected with the hook is in line with the longitudinal line of the link 12. Stirrups or guides 16 through which the links 12 pass freely are provided beneath the outer portion of the inclined bottoms 15 to prevent the possibility of the links dropping onto the track in case of their becoming broken. When it is desired to release the doors, the hand wheel 4 is turned in the proper direction and, through the friction of the hooks on the drums, the hooks will be disengaged from the winding drums and the further turning of the winding shaft will unwind the chains and permit the doors to swing open, as indicated in dotted lines in Fig. 2.

In Figs. 3 and 4 I have shown the invention applied to a hinged door in a flat bottom car. In this construction the winding shaft 1 is arranged below the car floor near the edge of the opening which is closed by the door, and the winding drums are omitted, the chain 10 being wound directly on the shaft. The links 12 are omitted and the hook 11 is pivotally connected at its shank to the outwardly bent lower end of a bracket 17 which is secured at its other end to the under side of the door near its edge. When the door is in closed position, as shown in full lines in Fig. 4, the line of strain, that is, the line drawn from the point of attachment of the hook 11 to the door

bracket 17 to the point of contact between the end of the hook and the shaft will fall beyond the center of the shaft. When the winding shaft is turned in a direction to unwind the chain, the friction between the hook and the shaft will readily release the hook and permit the door to drop to the position shown in dotted lines in Fig. 4. The pivotal connection of the hook to the end of the bracket prevents the hook from twisting.

In Figs. 5 and 6 I have shown the invention applied to a dump car in which two doors 13 are used meeting at the middle of the opening closed by them, the doors when released swinging in the direction indicated by dotted lines in Fig. 5. In this construction a link 12 is pivotally connected to each door and the two links are brought together at their upper ends and the ends of both pivotally connected to the shank end of the hook 11. The winding shaft 1 is provided with a winding drum 9 to receive the chain 10. The winding drum is provided with a ratchet wheel 20 with which a holding pawl 21 engages. When the doors are in closed position the line of strain, or lines of strain, will be nearly perpendicular and the load will be sustained by the end of the hook 11 which as in the construction above described is of such shape as to locate this line of strain beyond the center of the drum and shaft.

The device may, of course, be applied to other types of dumping cars than those above described in which a winding shaft either with or without winding drums are used for drawing or swinging a hinged door into closed position and affords in any such car a convenient and simple means for relieving the winding drum from torsional strain when in closed position.

Having thus described my invention what I claim is:

1. In a dumping car, the combination of a swinging door, a winding shaft, a substantially cylindrical drum mounted thereon, a flexible connection between the drum and the door having a portion thereof adapted to be wound on said shaft, and a hook forming a part of the flexible connection adapted to engage the drum at such a point on the periphery of the same that a line drawn from this point to the point of attachment of the flexible connection to the door will fall beyond the center of the drum, the hook being further adapted to rest against the drum at a point approximately ninety degrees behind the aforesaid point of contact between the hook and the drum, the portion of the hook between these points being cut back so as to clear the drum.

2. In a dumping car, the combination of a swinging door, a winding shaft, a substantially cylindrical drum mounted there-

- on, a flexible connection between the drum and the door having a portion thereof adapted to be wound on said shaft, and a hook forming a part of the flexible connection adapted to engage the drum at such a point on the periphery of the same that a line drawn from this point to the point of attachment of the flexible connection to the door will fall beyond the center of the drum,
- 10 the hook being further adapted to rest against the drum at a point approximately ninety degrees behind the aforesaid point of contact between the hook and the drum, the portion of the hook between these points being cut back so as to clear the drum, the forward edge of the hook as it is drawn toward the drum being chamfered.
3. In a dumping car, the combination of a swinging door, a winding shaft, a substantially cylindrical drum mounted thereon, a flexible connection between the drum and the door having a portion thereof adapted to be wound on said shaft, and a hook forming a part of the flexible connection with its inner end adapted to engage the drum at such a point on the periphery of the same that a line drawn from this point to the pivot point of the link on the door will fall beyond the center of the drum, the outer end of the hook being provided with a series of holes of slightly greater or less spacing than those in the aforesaid link, and a pin adapted to connect the inner end of the link to the outer end of the hook,
4. In a dumping car, the combination of a swinging door, a link pivotally connected thereto at one end, the other end being provided with a series of holes longitudinally of the link, a winding shaft, a substantially cylindrical drum mounted thereon, a flexible connection between the drum and the link having a portion thereof adapted to be wound on said shaft, and a hook, forming a part of the flexible connection with its inner end adapted to engage the drum at such a point on the periphery of the same that a line drawn from this point to the pivot point of the link on the door will fall beyond the center of the drum, the portion of the hook between these points being cut back so as to clear the drum, the contact between the hook and the drum being substantially a line longitudinally of the drum.
